UNITED STATES PATENT OFFICE

100,189

DESIGN FOR A HOT AIR GUN

Frans O. Albertson, Sioux City, Iowa, assignor to
Albertson & Company, Inc., Sioux City, Iowa, a
corporation of Iowa

Application February 28, 1936, Serial No. 61,403

Term of patent 14 years

To all whom it may concern:

Be it known that I, Frans O. Albertson, a citizen of the United States, residing at Sioux City, in the county of Woodbury and State of Iowa, have invented a new, original, and ornamental Design for a Hot Air Gun, of which the following is a specification, reference being had to the accompanying drawing, forming part thereof.

The figure is an elevational view of the hot air gun, with the air discharge nozzle extending downward and the handle upward. The

dominant feature of my design resides in the portion shown in full lines.

The hot air gun body is substantially cylindrical in cross section, and the other side of the hot air gun looks like the side shown.

I claim:

The ornamental design for a hot air gun, as shown and described.

In witness whereof, I hereunto subscribe my name, this 25 day of Feb., 1936.

FRANS O. ALBERTSON.
